UNITED STATES PATENT OFFICE.

ROBERT ASHE, OF SOMERVILLE, ASSIGNOR TO JOHN F. CURTIS, OF BOSTON, MASSACHUSETTS.

TACK-DRIVING MECHANISM FOR LASTING BOOTS OR SHOES.

SPECIFICATION forming part of Letters Patent No. 341,823, dated May 11, 1886.

Application filed October 12, 1885. Serial No. 179,731. (No model.)

To all whom it may concern:

Be it known that I, ROBERT ASHE, of Somerville, in the county of Middlesex and State of Massachusetts, have invented a new and useful Improvement in Tack-Driving Machines for Lasting Boots and Shoes, of which the following, taken in connection with the accompanying drawings, is a specification.

My invention has for its object the construction of a machine that shall be sure in its action and not liable to get out of order, and simple in construction. These objects I attain by the mechanism shown in the accompanying drawings, in which—

Figure 1 is a side elevation of my machine. Fig. 2 is an elevation of a part viewed from the opposite side from which Fig. 1 is taken, showing the device for stopping the tack-driving mechanism when the boot or shoe is removed. Figs. 3 and 4 illustrate the details. Fig. 5 shows in elevation the main shaft, driving-pulley, friction-pulley, and clutch and cam for operating the driving mechanism. Fig. 6 is a longitudinal section of a part of the tack slide or trough and some of its connecting parts. Fig. 7 is a plan of the same. Fig. 8 is a section taken on line X X of Fig. 6, and Fig. 9 is a detail showing the parts that are immediately connected with delivering the tack to the action of the driver.

In the drawings, A represents the post upon which the machine is supported.

B and B' are parts which constitute the frame-work of the machine, and to which the working parts are attached.

C, Figs. 1 and 5, is the main shaft of the machine. Upon the shaft C, I have a quill, C⁵, Fig. 5, attached to one end of which is the driving-pulley C⁴ and to the other end the pulley C². The quill C⁵ and its attached pulleys C⁴ C² can be moved slightly lengthwise on the shaft C by means of the lever C⁶, which operates in the groove C³, Fig. 5.

The interior of the pulleys C², together with the cone C⁷, which is rigidly attached to the shaft C, form a friction-clutch, so that when desirable the shaft C may be made to revolve, and through the cam C' operate the tack-driving mechanism.

D, Figs. 1 and 5, is the belt extending from the pulley C² to the worm-wheel D', which,

acting through the gear D², operates the tack-supplying wheel D³. (See Figs. 1 and 4.) The wheel D³ is located in the tack-reservoir D⁴, and surrounds the end of the tack-trough E, as shown, so that in its revolutions it is constantly taking tacks from the lower part of the reservoir D⁴ and carrying them in the recesses d, Fig. 4, above the trough E and dropping them upon it, so as to keep the said trough E constantly supplied with tacks. This action of the tack-supplying wheel D³ is going on whether the tack-driving mechanism is at work or not, so that the tack-trough E is always full of tacks, these tacks being in position, as illustrated at E², Fig. 6, the trough E being sufficiently inclined, so that the tacks E² will slide down by their own gravity to the delivery-recess H', Figs. 1 and 9.

To prevent more than one tack being delivered at a time, I have the following device, (shown more particularly in Figs. 6, 7, and 8.) This device consists of a reciprocating bed-piece, F³, which has upon it projections F⁴ F⁵ F⁶, (see Figs. 7 and 8,) which are arranged to act similar to the escapement of a watch or clock—that is, when one of the points, F⁴, for instance, passes through the tack-raceway, as shown in Figs. 7 and 8, sufficiently far to hold the tacks from sliding down, its corresponding point, F⁵, is clear from the raceway; but at the next oscillation of F³ it will enter the raceway E' above the last tack, and, as at the time of this entrance of F⁵, F⁴ is withdrawn so that the tack held by it can slide into receptacle H'. At the next operation of the rod F³ the tack held by F⁵ will be released and retained by F⁴ until another oscillation takes place—that is, one tack will be released at each oscillation of the bar F³.

F⁶, Figs. 6, 7, and 8, is a plate attached to the oscillating bar F³, and forces the released tack into the throat under the driver-tacks. Oscillation is imparted to the bar F³ by means of the lever F, Figs. 1 and 7. This lever F has a recess at F², in which the lower end of the lever F operates, the lever F⁷ being pivoted to the frame of the machine at F⁸, Fig. 1. The upper end, F⁹, of the lever F has attached to it a fixed pin, F¹⁰. (See Figs. 1 and 3.) This pin F¹⁰ enters the cam-groove G, Fig. 3, formed in a bracket, G', which is made fast to

the oscillating arm M, Figs. 1 and 3, so that at each up and down stroke of the arm M motion is communicated to the lever F, oscillating bar F³, and escapement-points F⁴ F⁵ F⁶.

5 I will now describe the tack-driving mechanism. M, Fig. 1, is the driving-rod, and is attached to a sliding part, M', which has upon its upper end a pin and friction block, M³, which is embraced by the forked end M² M² of the lever M. This lever M is pivoted to the frame of the machine at M' and is made to work by means of the cam C'. Cam-pin L', Figs. 1 and 5, is attached to the lever L, which, swinging on the fixed pin L², acts through the pin L³, pitman L⁴, and pin L⁵, and thus operates the lever M.

10 The tack-receiving hopper H¹, Figs. 1, 6, and 9, is formed at the junction of two levers, H H', Fig. 9. These levers are pivoted to the part E by pivots h h, and held together by a spring, H³. The receptacle H¹ is cone-shaped, and has in the lower part an opening just large enough for allowing the blade of the tack to pass through it, but not large enough to allow 15 the head to go through, so that the tack will remain suspended until the driving-rod M strikes it, which will force it through, the levers H H' yielding laterally to admit of the passage of the tack-head. The tack after leaving the receptacle H¹ passes through the hollow presser-foot.

20 To prevent the tack-driving mechanism from operating when the shoe is removed from the machine, I have the device shown in Fig. 2. 25 This consists of a bell-crank lever, K K³, which

is pivoted to the frame of the machine, as shown at K'. The upper end, K³, of this lever engages in a notch formed in the bracket-piece K⁴ K⁵, and is there held by K², unless thrown out by the means that I will now describe. The presser-foot H² is attached to a sliding part, H⁶, which is guided by the screws H' H' in the slots h h. This slide H⁶ has a projection, H⁸, upon which the lower end, K, of the lever K K³ rests. When the shoe is placed 40 in position for being tacked, it forces the presser-foot H² and the slide H⁶ upward. This causes the projection H⁸ to force the lever K K³ into such a position as to throw out its end K³ from the notch in K⁴. This action will leave 45 the lever M free to operate so long as the shoe is in place.

I claim—

1. In a machine for driving tacks, the combination of the tack-trough E and reciprocating bed-piece F³ with the escapement projections F⁴ F⁵ F⁶, all operating together substantially as described, and for the purpose set forth. 55

2. In a machine for driving tacks, the combination of the driving-pulley C, quill C³, sliding device C³ C⁶, and pulley C² with the shaft C, cam C', lever F, link L⁴, and working-lever M, all operating together substantially as described, and for the purpose set forth. 60

ROBERT ASHE.
